UNITED STATES PATENT OFFICE.

DAVID WILEY ANDERSON, OF SCOTTSVILLE, VIRGINIA.

FLASHING BRICK OR BLOCK.

Application filed March 27, 1926. Serial No. 97,901.

This invention relates to a new and novel roof fastening or flashing means to be utilized in connection with masonry, brick or other construction of walls.

5 The prime object of the invention is to provide simple, durable, practical, and efficient means for securing any suitable roofing material to the wall, that will function effectively and thus prevent leakage, at a 10 minimum cost.

Another object of the invention is to so construct my improved flashing means that the next layer of brick or masonry forms a 15 complete flashing groove for the reception of the flashing material and its securing means. Another object of the invention is to so construct my novel flashing brick or block that it can be made the thickness of an ordinary brick.

20 Further objects of this invention are to so construct the improved brick or block that it provides means to prevent the access of mortar to the flashing groove during the process of laying; to furnish additional 25 anchorage for the waterproof roofing cement which is packed into the flashing groove; to furnish anchorage means for the mortar in the lower face of the brick, and to prevent any possibility of water or dampness soaking 30 down into the wall.

The foregoing and such other objects as may appear from the ensuing description are accomplished by the combination, construction, arrangement and location of the 35 several parts hereinafter more fully described, illustrated in the accompanying drawings and particularly pointed out in the claims appended hereto, it being understood that slight changes in the precise form, proportions and minor details of the construction 40 may be resorted to without departing from the spirit or sacrificing any of the advantages of the invention.

In the accompanying drawings forming a 45 part of this specification it will be seen that:—

Figure 1 is a transverse section view showing my invention used to connect a roof with a parapet wall.

50 Figure 2 is a perspective partly in section showing the wall broken away.

Figure 3 is a perspective of the flashing brick or block removed from the wall.

55 Figure 4 is an enlarged transverse section showing the flashing or roofing material secured thereto.

Figure 5 is an enlarged transverse section showing a slightly modified form.

Figures 6, 7, 8 and 9 are enlarged transverse sectional views of slight modifications, 60 and

Figure 10 is a perspective showing the vertical joints of the flashing bricks or blocks bonded and broken by the course of masonry or brick immediately above which forms the 65 upper or ceiling portion of the flashing grooves.

In the embodiment of my invention as illustrated in Figs. 1 to 4, it will be seen that the numeral 1 designates the flashing brick 70 or block, when placed or laid in the wall with the next above layer of brick or masonry 2 forms a complete groove 3 for the reception of the flashing or roofing material, said brick or block being formed with 75 a central upward extension 4, to prevent the access of mortar to the said groove during the building process, while the outer and upper surface of the brick or block is formed with a concave depression 5 forming an 80 anchorage for the reception of the waterproof cement 6, a convex surface 7 forming a seat or rest for the upper end portion of the flashing or roofing material 8, which is projected into the said groove and properly secured therein by the said waterproof cement, the inner terminal of the groove 3 being formed by the vertical or upright wall portion 9 of said brick or block. 85

By reference to Fig. 5 of the drawings, it 90 will be perceived that the brick or block is formed with an upper surface 10, which inclines or slopes inwardly and downwardly for the reception of the flashing or roofing material 11, which is suitably secured within 95 the groove formed between said upper surface and the course of brick or masonry 11' above it by suitable waterproof cement 12 in the manner shown, and formed in the lower face of the brick is a recess 13 for the 100 reception of mortar, thereby forming an additional anchorage or locking means for said brick.

As illustrated in Fig. 6 of the drawings it 105 will be seen that two slightly modified forms of brick or blocks 18 are shown, one disposed directly above the other, showing their use where it is desirable to employ two or more flashing grooves 19 for the reception of additional counter flashing or roofing material. 110

The slightly modified form of brick or block illustrated in Fig. 7, shows the upper face

thereof formed with a downwardly and outwardly inclined or sloping surface 14 forming a seat or rest for the flashing or roofing material 15, said sloping surface terminating at its 5 upper end with a concave depression 16, constituting anchorage means for the reception of the desired waterproof cement 17, for securing said material 15 within the groove formed between the sloping surface, the concave depression, and the course of masonry or brick directly above said sloping surface 14, while the brick or block shown in Fig. 8 10 shows an upper surface formed in substantially the same manner as that shown in Fig. 15 7 forming a seat for the upper end portion of the usual fibre and plastic cement roofing material 20 which is secured within the groove by the plastic cement after the roofing material is placed within said groove.

20 As shown in Fig. 9, the flashing brick or block 21 is formed with a more abruptly inclined upper bearing surface 22 for the upper end portion of the felt and plastic cement roofing material 23, placed on the roofing boards 24, said material being secured within the groove formed between the upper surface of the brick 21, and the next course above of masonry or brick 25, by filling in the groove with plastic elastic roofing cement 26 the depression 26' forming an anchorage for said cement, the lower face of said brick or block being formed with a recess 27 therein constituting a locking means for the mortar and the brick or block.

35 In the perspective view shown in Fig. 10, it will be seen that the vertical joints between the flashing bricks or blocks 28 are bonded or broken by the masonry or course of brick 29 immediately above which forms 40 the upper or ceiling portion of the flashing grooves 30, thereby insuring effective and practical means for securing the roofing to the wall or groove and preventing leakage.

45 While, as illustrated, my novel brick or block is shown with a partial hollow body portion, it will be readily obvious that the said brick or block may be formed solid, and

while it is preferred to form the brick or block of vitreous clay it may be formed from any suitable material. Further, it is understood that my improved brick or block may be formed of any suitable or desirable thickness or dimensions required for its successful and practical utilization.

50 It will be perceived that the extension 4 projecting upwardly from the brick or block regulates the depth of the flashing groove; forms a dam or stoppage of mortar from entering said groove in the process of laying the masonry, and an effectual stop for regulating the level of the bed or surface of the next course of brick or masonry above said brick or block.

55 Having thus described my invention what I claim and desire to secure by Letters Patent is:—

1. A flashing block formed with a longitudinal projection extending above its upper face and provided with a depression below such face and to the other side thereof 70 and such projection.

2. A flashing brick or block formed with a longitudinal projection extending above its upper face the entire length of said brick, and provided with a depression below such face and to the other side of the face and projection.

3. A flashing brick or block formed with a longitudinal projection above its upper face, a recessed portion disposed below said face and to the other side of said face and projection, and a mortar anchorage depression formed in its lower face.

4. Flashing means of the character described, comprising a brick or block formed with a longitudinal projection above its upper face and a depression below said face and to the other side of the face and said projection, said block forming in connection with the building material disposed above 85 it a groove for the reception of roofing material.

90 DAVID WILEY ANDERSON.
